ATTORNEYS.

UNITED STATES PATENT OFFICE.

HELEN M. TEN BROOK, OF SYRACUSE, NEW YORK.

BUSTLE.

SPECIFICATION forming part of Letters Patent No. 695,420, dated March 11, 1902.

Application filed February 20, 1901. Serial No. 48,046. (No model.)

To all whom it may concern:

Be it known that I, HELEN M. TEN BROOK, of Syracuse, in the county of Onondaga, in the State of New York, have invented new and 5 useful Improvements in Bustles, of which the following, taken in connection with the accompanying drawings, is a full, clear, and exact description.

My invention relates to improvements in 10 bustles.

The object of this invention is to provide light and durable means whereby the skirts are held firmly in position up to the waist-line, the shirt-waist or other similar garment 15 is prevented from creeping or otherwise drawing up from the belt, and the load of the skirts is transmitted to the shoulders of the wearer, thereby serving a hygienic purpose and causing the dress of the wearer to always 20 present a neat and tidy appearance.

The further object of my invention is to construct the parts of a bustle in such manner that the bustle may be readily made to conform to the contour or shape of the body 25 when placed in operative position and always maintains its symmetry of form under all conditions and uses without liability of matting or getting out of place.

To this end the invention consists in the 30 combination, construction, and arrangement of the parts of a bustle or skirt-supporting device, as hereinafter fully described, and pointed out in the claims.

Referring to the drawings, Figure 1 is a 35 perspective view of the bustle embodying my invention. Fig. 2 is an inner face view, partly broken away, of the body of the bustle and the band and fastening-plate secured thereto, portions of the band being broken away and 40 the inner lining of the body being also broken away for disclosing the position and arrangement of the stays. Figs. 3 and 4 are sectional views taken, respectively, on lines 3 3 and 4 4, Fig. 2. Fig. 5 is an isometric view 45 of the detached fastening-plate.

Similar reference characters indicate corresponding parts in all the views.

It is well known that considerable difficulty 50 is experienced in holding the skirts and shirt-waist of the wearer to the waist-line, that the skirts almost invariably sag at the back, that the shirt-waist is more or less liable to

creep sidewise or draw up from the belt or skirt-band, and that the load of the skirts rests upon the hips of the wearer. I have 55 sought to overcome these difficulties by providing the bustle with a suitable toothed plate secured to the band of the bustle, which is adapted to engage a corset lace or cover, or when the shirt-waist is worn to engage the 60 shirt-waist for holding the skirts up to the waist-line and for transmitting the load to the shoulders of the wearer, which at the same time serves to hold the shirt-waist in position.

As seen in the drawings, this invention consists of a bustle-body A, having a band a and a toothed fastening member B, secured to the band a.

The bustle-body A may be of any desired form or size, is usually composed of inner 70 and outer layers of fabric 1 and 2 and a filling or padding 3, interposed between said fabric layers, the edges of said layers being secured together by suitable stitching for forming a sack, which retains the padding 75 3 in position.

The waistband a is secured to the upper edge of the body A and is formed with suitable straps a', which are adapted to be tied around the waist for partially supporting the 80 bustle in position.

The plate B is preferably formed of metal, is secured to the inner face of the waistband a by suitable fastening means, as rivets or eyelets 4, passed through the waistband and 85 ends of the metal-plate, leaving the intermediate portion free from securement to the band, and its lower edge is provided with depending teeth 5, which are adapted to engage the lace or casing of the corset, or a shirt-waist 90 when worn, said plate being usually formed of thin sheet metal, having its end and upper edges formed substantially smooth and unbroken in order to economize in the manufacture of the plate and also to prevent undue 95 abrasion of the wearing-apparel.

In order that the body of the bustle may always maintain its proper form and elasticity, I preferably provide the same with opposite upright spring-stays 6, secured to the 100 opposite ends of the body A and preferably to the inner face of the inner layer 1 of said body, said stays having their opposite ends extended in proximity to the upper and lower

edges of the body A at opposite ends of the plate. Secured to the lower edge of the body A is an additional stay 7, extending transversely of said body from side to side in a plane substantially parallel with the band *a* and having its upper ends extended beneath and in proximity to the lower ends of the upright stays 6, said stay 7 being also formed of spring-steel or equivalent material. The upright stays 6 serve to tension the fabric vertically for holding the body in its upright position, and the stay 7 serves to tension the lower edge of the fabric laterally. Interposed between the upright stays 6 and between the lower stay 7 and band *a* are a series of transverse diagonal stays 8, 9, 10, and 11, said stays 8, 9, 10, and 11 being also secured to the inner face of the lining 1 of the body A. These stays are preferably arranged at an angle with the band *a* and lower stay 7 and usually extend diagonally entirely across the face of the body A between the upright stays 6. The stays 8 and 10 are arranged substantially parallel with each other, the stay 8 having one end arranged in proximity to the upper end of one of the upright stays 6 and its other end arranged in proximity to the intermediate portion of the opposite stay 6, and the said stay 10 is arranged with one of its ends in proximity to the lower end of said opposite stay 6 and its other end in proximity to the intermediate portion of the former upright stay 6. The stays 9 and 11 are also arranged substantially parallel with each other and in planes intersecting, respectively, the stays 8 and 10, corresponding ends of the stays 8 and 11 being arranged in proximity to each other and to the intermediate portion of one of the upright stays and are extended in diverging directions toward the other upright stay, their opposite ends being disposed in proximity to the opposite ends of the other upright stay 6. In like manner corresponding ends of the stays 9 and 10 are arranged in proximity to each other and to the intermediate portion of one of the upright stays 6 and are extended in diverging directions toward the opposite ends of the opposite upright stay 6. It is thus evident that the several stays form particularly light and durable means for retaining the body A of the bustle in its extended position and that by arranging the intermediate stays 8, 9, 10, and 11 in diverging and intersecting planes the body of the bustle is not only extended or tensioned laterally, but is also tensioned vertically, by reason of the fact that when the body of the bustle is bent or curved the tendency of the portions of the intersecting stays at opposite sides of their point of intersection is to expand the portions of said body secured to the outer ends

of said intersecting stays. These stays are usually inclosed in the usual fabric sheathing, which permits the same to be readily secured to the fabric of the body A, the ends of said stays being also provided with the usual caps for preventing abrasion of the adjacent portions of the fabric. 65

Secured to the lateral edges of the inner lining 1 are suitable straps *b*, which are adapted 70 to be tied or otherwise fastened together for effecting the proper curvature of the body of the bustle.

Secured to the band *a* and depending therefrom at the opposite sides of the body A are 75 hip pockets or pads A', which are preferably open at their upper ends for permitting the insertion or removal of the padding, as may be desired, the remaining edges of said pockets or pads being stitched together for retaining 80 the padding in position.

The operation of my invention will now be readily understood upon reference to the foregoing description and the accompanying drawings, and it will be noted that some 85 change may be made in the detail construction and arrangement of my invention without departing from the spirit thereof.

Having thus described my invention, what I claim, and desire to secure by Letters Patent, is—

1. A bustle comprising a waistband having a depending body of fabric or equivalent material, upright spring-stays secured to the opposite ends of the body, and a transverse 95 spring-stay secured to the lower edge of the fabric body and having its opposite ends in close proximity to the lower ends of the upright stays, and a flat metal plate secured to the inner face of the waistband in a position 100 above and between the upper ends of the upright stays and substantially parallel with the lower transverse stay and provided with depending teeth for the purpose described.

2. A bustle comprising inner and outer layers of fabric or equivalent material, spring stays or bars extending diagonally in intersecting planes across and between the layers of fabric and secured thereto, upright stays secured between the layers and extended upwardly from the lower ends of the former stays, and a metal plate secured to the inner face of upper edge of the bustle above and between the upper ends of the upright stays and provided with depending teeth for the 115 purpose set forth.

In witness whereof I have hereunto set my hand this 18th day of February, 1901.

HELEN M. TEN BROOK.
